COMBINED GAS-FIRED FURNACE AND DUCT CASINGS THEREFOR

Ralph R. Hodges, Belleville, Ill., assignor to Empire Stove
Company, Belleville, Ill., a corporation of Illinois

Filed Nov. 7, 1967, Ser. No. 9,310

Term of patent 14 years

U.S. Cl. D23—110
Int. Cl. D23—03

FIG. 2

FIG. 3

FIG. 4

FIG. 5

FIG. 6

FIG. 1 is a perspective view of the combined gas-fired furnace and duct casings therefor embodying my design positioned within a room adjacent to the walls thereof.

FIG. 2 is a top plan view thereof.

FIG. 3 is a front elevational view of the furnace, the duct casings being omitted for convenience of illustration.

FIG. 4 is a left end view thereof.

FIG. 5 is a right end view thereof.

FIG. 6 is a front elevational view of a portion of the duct casings with the furnace and remaining duct casings omitted for convenience of illustration.

The broken line disclosure is for illustrative purposes only.

I claim:

The ornamental design for a combined gas-fired furnace and duct casings therefor, substantially as shown and described.
